PROCESS FOR TREATING REFINED OIL

Benjamin H. Thurman, Bronxville, N. Y., assignor
to Refining, Inc., Reno, Nev., a corporation of
Nevada

Application March 5, 1938, Serial No. 194,226

9 Claims. (Cl. 260—428)

This invention relates to a process of treating refined animal and vegetable oils, and more particularly to a process of removing residual impurities from such oil after it has been treated with alkali and the resultant soap stock separated from the oil.

In processes of refining animal and vegetable oils by an alkali treatment, the oil, after the resultant soap stock has been separated therefrom either by a settling or centrifugal separation step, contains small amounts of residual alkali, soap and water. This refined oil has been treated by adding water, agitating to mix the water with the oil and then separating the water either by a gravity settling and decantation step or by centrifugal separation. Any water remaining in the oil was then conventionally removed by vacuum drying to vaporize the water from the oil.

The agitation of the water with the oil during the washing step, particularly in the presence of air, formed an emulsion which caused difficulty in separating the water from the oil, especially where it was attempted to perform the separation centrifugally. Thus substantial amounts of water with dissolved impurities were retained in the oil after such gravity or centrifugal separation, which required vacuum drying equipment of large capacity and also resulted in leaving deleterious quantities of alkali and soap in the dried oil.

In accordance with the present invention, the oil is washed in a closed system by introducing a stream of water into a stream of the oil to be washed. Mixing is accomplished out of contact with the atmosphere and without mechanical agitation. This washing operation does not form the difficultly separable emulsion above referred to, and substantially all of the water containing dissolved impurities can be removed from the oil by continuous centrifugal separation. The amount of water left in the separated oil is extremely small, and can be easily removed from the oil by vacuum drying equipment of relatively small capacity without leaving deleterious amounts of soap and alkali in the oil.

Also, in the case of animal and vegetable oil which has been centrifugally separated from soap stock after alkali treatment of the oil, agitation of the mixture of oil and soap stock in the entrance of the centrifugal in the presence of air, and also the agitation due to discharge of the separated oil as the lighter effluent from the centrifugal bowl in the presence of air, frequently causes considerable air to be retained in the oil. The retained air appears to be pres-

ent in a complex emulsion of oil, soap, water and air. This emulsion will collect on the surface of a quiescent body of oil that has been discharged from the refining centrifugal in the form of a jelly and appears to be primarily of the water-in-oil type, such that it is not dissolved by water. This complex emulsion is not, therefore, effectively washed from the oil by washing with water followed by centrifugal separation, but substantial amounts of soap and alkali are retained in the washed and separated oil.

In accordance with the present invention, it has been found possible to break the complex emulsion referred to and render the soap and alkali contained therein readily removable from the oil by a washing and separation operation. By introducing the oil discharged from the refining centrifugal into a de-aerating chamber and retaining it in said chamber for a substantial length of time, the air can be removed from the complex emulsion above referred to. This can be accomplished by slowly agitating the oil in open tanks so that the air is liberated into the atmosphere, taking care that the agitation is not sufficient to beat air back into the oil, but it is preferred to maintain the oil discharged from the refining centrifugal out of contact with the atmosphere, as it is ordinarily at a temperature between 100° F. and 160° F. at the time of discharge. Particularly at the higher temperatures in this range, the oil tends to darken in contact with the atmosphere. It is preferred, therefore, to de-aerate the oil in a closed chamber under vacuum conditions. The vacuum rapidly removes the air contained in the complex emulsion above referred to and renders the impurities therein soluble in water so that it can be easily removed by a washing and centrifugal separation step.

It is, therefore, an object of the present invention to wash previously alkali refined oil by mixing a stream of the same with a stream of water, out of contact with the air and without mechanical agitation, and then continuously separating the water containing dissolved impurities from the oil.

Another object of the invention is to provide a process of washing refined animal and vegetable oils in which the oil is mixed with water without forming a difficultly separable emulsion, and the water containing dissolved impurities continuously separated from the oil.

Another object of the invention is to provide a process of continuously washing refined animal

and vegetable oils so as to leave only small amounts of water containing dissolved impurities in the oil, thereby reducing the amount of drying of the oil subsequently necessary.

- 5 Another object of the invention is to provide a process of removing residual impurities from refined animal and vegetable oils in which the oil is subjected to a de-aerating treatment prior to washing and drying.
- 10 Still another object of the invention is to provide a process of removing residual impurities from animal and vegetable oils centrifugally separated from soap stock in the refining process, in which air is removed from the separated oil 15 prior to washing the same.

A further object of the invention is to provide an improved apparatus for washing refined oils, in which mechanical agitation is avoided.

- 20 A still further object of the invention is to provide an apparatus for de-aerating refined animal and vegetable oils, and then washing and drying the same.

Other objects and advantages of the invention will appear in the following description of the 25 process and the apparatus shown in the attached drawings, of which:

Figure 1 is a diagrammatic drawing of a complete system for de-aerating, washing and drying; and

- 30 Figure 2 is a similar view of a modified de-aerating apparatus.

Referring to the drawings, and more particularly to Figure 1: 10 indicates a refining centrifugal for separating soap stock from refined 35 oil following an alkali treatment thereof; 11 indicates in general a novel de-aerating system for removing the contained air from the separated oil; 12 indicates, in general, a proportioning and flow mixing device for mixing a stream of water 40 with a stream of oil; 13 indicates a centrifugal separator for continuously separating the water containing dissolved impurities from the oil; 14 indicates a vacuum drying chamber for the oil separated from the water; and 15 indicates in 45 general a vacuum and condensing system for maintaining a vacuum in the vacuum drying chamber 14 and the de-aerating apparatus 11.

A mixture of oil and soap stock from a refining operation, which may be a continuous refining 50 operation, such as disclosed, for example, in the patents to Clayton et al. Nos. 1,100,274; 2,100,- 275, is introduced into the refining centrifugal 10 through a pipe 16. The soap stock is therein separated from refined oil and discharged as a 55 heavy effluent from the discharge member 17 into the receptacle 18. The refined oil is discharged as the lighter effluent through a pipe 19, and is preferably delivered into a float tank 20 or similar device for preventing loss of vacuum in the 60 de-aerating system hereinafter described. The float tank 20 may be provided with a vent 21 and contain a float 22 pivoted at 23 for closing a valve indicated diagrammatically at 24 when the oil in the float tank 20 reaches a predetermined 65 lower level. When the level of the oil in the tank 20 is above this predetermined minimum level, oil is withdrawn through a pipe 25 and delivered alternately through pipes 26 and 27 into de-aerating chambers 28 and 29, respectively. The pipes 26 and 27 are provided with 70 manually operable valves 30 and 31 which are open during normal operation of the de-aerating system, and valves 32 and 34, respectively, operable by fluid pressure under control of the oil 75 levels in the chambers 28 and 29, as hereinafter

described. The valve 32 is shown in its normally open position, when fluid pressure is not applied to the diaphragm chamber 34, while the valve 33 is shown in its closed position due to fluid pressure applied to its diaphragm chamber 35.

5 The de-aerating chambers 28 and 29 may be identical in construction, and only one will be described in detail. Thus the chamber 28 is a closed chamber and is preferably provided with an agitator 36 having a shaft 37 extending 10 through a packing gland 38 and rotated from any suitable source of power through a pulley 39. The chamber 28 is also preferably provided with a heating coil 40 through which any desired heating medium, such as steam or hot water, may be 15 passed to maintain a desired temperature in the chamber 28. The chamber 28 is also preferably provided with an external float chamber 41 positioned adjacent the lower portion thereof and connected thereto by a pipe 42 provided with a 20 check valve 43 for preventing oil from flowing into the float chamber from the lower portion of the de-aerating chamber, but permitting oil to flow from the float chamber 41 into the de-aerating chamber. The float chamber 41 is also 25 connected to the upper portion of the de-aerating chamber through a pipe 44 and a plurality of pipes 45 connected to the de-aerating chamber at a plurality of levels and provided with manually operable valves 46. The level of oil reached 30 in the de-aerating chamber 28 before oil flows into the float chamber 41 can be determined by the valves 46, as oil will not flow into the float chamber 41 until the oil level has reached the height of the lowest open valve 46 because of the 35 check valve 43. A vent pipe 47 also connects the top of the de-aerating chamber 28 with the float chamber 41 to prevent trapping of air therein. The float chamber 41 contains a float 48, pivoted at 49 and arranged to operate a fluid control 40 valve 50 through a lever 51 slidably connected to a valve plunger 52 by a pin 53 and slot 54 in the plunger 52. The float 48 and valve 50 are utilized to control the admission and withdrawal of oil from the de-aerating chambers 28, as will be 45 hereinafter described.

The de-aerating chamber 29 is likewise provided with a similar float chamber 41' connected to the chamber by a pipe 42' having a check valve 43' therein; a pipe 44' and a plurality of 50 pipes 45' at different levels, each provided with a manually operable valve 46'; and by a vent pipe 47'. The float chamber contains a float 48' pivoted at 49' and operating a fluid control valve 50' through a lever 51' slidably connected to a 55 valve plunger 52' by a pin 53' and slot 54'. Interlocking means is provided between the fluid control valves 50 and 50'. This means may include a bell crank lever 55 pivoted at 56 and having one arm engaging a shoulder on the valve 60 plunger 52 and the other arm pivotally connected to a link 57 also pivotally connected to one arm of a bell crank lever 55' pivoted at 56' and having the other arm engaging a shoulder on the valve plunger 52'. 65

Oil is withdrawn alternately from the de-aerating chambers 28 and 29 through pipes 58 and 58' respectively. The pipe 58 is provided with a fluid pressure operated valve 59, having a diaphragm chamber 60 and a check valve 61 for 70 preventing return flow of oil into the chamber 28. The valve 59 is shown in its normally closed position when no fluid pressure is applied to diaphragm chamber 60. In a similar manner, the pipe 58' is provided with a fluid pressure 75

operated valve 59' having a diaphragm chamber 60' and a check valve 61' for preventing return flow of oil into the de-aerating chamber 29. The valve 59' is shown in its open position due to fluid pressure applied to the diaphragm chamber 60'. The pipes 58 and 58' are connected at their ends remote from the de-aerating chambers to a common oil withdrawal pipe 62 leading to a heating device 63 through which oil is drawn alternately from the de-aerating chambers 28 and 29 by the proportioning pump 64 driven by a variable speed motor 65. The floats 48 and 48' may also be employed to open electrical contacts 66 and 66', respectively, which contacts may be connected in parallel in the power supply circuit (not shown) of the motor 65 so as to stop this motor when the floats are both in their lowermost position.

The plunger 52 of the fluid control valve 50 may have a port 67 therethrough which, in the uppermost position of the plunger 52 registers with a pipe 68 connected to a source of fluid pressure, for example, city water mains. In the lowermost position of the plunger 52, the port 67 registers with an exhaust pipe 69. The port 67 registers in both positions with a pipe 70 leading to the diaphragm chambers 34 and 60 such that the valves 32 and 59 are in their normal position as shown when the plunger 52 is in its lowermost position. When the plunger 52 is in its uppermost position, the pipe 70 is connected to the source of fluid pressure, so that fluid pressure is applied to the diaphragm chambers 34 and 60 to close valve 32 and open valve 59.

The plunger 52' of the valve 50' is likewise provided with a port 67' which will connect the pipe 70' with a source of fluid pressure through pipe 68' or release the pressure applied through the pipe 70' by connecting it to an exhaust pipe 69'. The plunger 52' thereby applies fluid pressure through the pipe 70' to the diaphragm chambers 35 and 61' to close valve 33 and open valve 59' when the plunger 52' is in its uppermost position and allows the valve 33 to be in its normally open position and the valve 59' to be in its normally closed position when the plunger 52' is in its lowermost position.

As stated before, a vacuum is preferably maintained in the chambers 28 and 29, and these chambers may be connected by pipes 71, 71' and 72 to a condenser 73 connected to a vacuum pump 74. The condenser 73 may be of the conventional jet type, into which water is introduced through the pipe 75 and from which water may be withdrawn from the barometric column 76 extending below the surface of water in the receptacle 77.

The operation of the de-aerating system above described is as follows: In starting out, chambers 28 and 29 may be empty, such that the floats 48 and 48' are in their lowermost position and the motor 65 is not driving the pump 64. The plunger 52 and 52' may be in the position shown or may be shifted thereto manually and all of the manually operable valves in the pipes 26, 27, 58 and 58' may be open. Oil will flow through the pipes 25 and 26 into the chamber 28, as there is a vacuum maintained therein by the vacuum and condensing system 15 above described. As valve 59 is closed, the oil will rise in the chamber 28 until the level of an open valve 46 is reached. The level reached in chamber 28 and, therefore, the time the oil is allowed to remain in the chamber 28 can thus be controlled

by opening a desired valve 45. During the filling of chamber 28, oil does not flow into the float chamber 41, because of the check valve 43, until it reaches the level of an open valve 46, at which time oil flows into the float chamber 41 through the open valve 46. Oil flowing into chamber 41 raises the float 48 to raise the plunger 52 connected thereto to apply fluid pressure to the diaphragm chambers 34 and 60 of the valves 32 and 59, thus closing valve 32 to stop the flow of oil into the chamber 28 and opening valve 59 to permit oil to discharge through pipe 58 from chamber 28. Raising of the plunger 52 depresses plunger 52' of fluid control valve 51', through the interlocking mechanism including bell cranks 55 and 55' and link 57, to apply fluid pressure to diaphragm chambers 35 and 60' so as to open valve 33 and close valve 59'. Raising of the float 48 also starts the motor 65 by allowing contacts 66 and 66' to close. The system will then continue to work automatically, oil will be withdrawn from chamber 28 while chamber 29 is being filled. When the level in chamber 28 approaches the bottom of the chamber, oil will flow from the float chamber 41 associated therewith into the chamber 28, thus allowing float 47 to fall. If this occurs before a level is reached in chamber 29 which causes oil to flow into the float chamber 41', the contacts 66 and 66' will be opened to stop motor 65 and withdrawal of oil until float 48 is raised. When oil flows into float chamber 41', plunger 52' of fluid control valve 50' is raised and at the same time plunger 52 of fluid control valve 50 is depressed by the interlocking mechanism. This causes valves 32 35 and 59' to be opened and valves 33 and 59 to be closed and at the same time starts motor 65 so that oil is withdrawn from chamber 29 as chamber 28 is filled. If it should happen that chamber 28 becomes filled up to a level at which oil enters float chamber 41 before chamber 29 is emptied, the floats can be balanced so that they will not move until oil flows out of float chamber 41' due to the emptying of chamber 29. Thus one de-aerating chamber will always be emptied before oil is withdrawn from the other. The above described operation will repeat indefinitely, with chamber 28 filling while chamber 29 is being emptied, and chamber 29 filling while chamber 28 is being emptied. By correlating the rate of withdrawal from the de-aerating chambers with the rate of flow into these chambers, for example by adjusting the speed of motor 65, continuous withdrawal is effected, without interruption by stoppage of motor 65.

Agitation of the oil in de-aerating chambers 28 and 29 under vacuum conditions is effective to remove the air from the oil, thus effectively breaking the complex emulsion above described. As before stated, a similar result can also be accomplished by agitating the oil or even merely allowing it to stand in an open tank. However, vacuum de-aerating is preferred, and if desired, a controlled amount of moisture can also be withdrawn from the oil in the chambers 28 and 29, depending upon the time of treatment therein, the temperature of the oil and the degree of vacuum, in order to further assist in breaking said complex emulsion.

Thus, a stream of de-aerated, and if desired at least partially dried, oil can be continuously pumped from the de-aerating system through the pipe 62 by means of the pump 64. In order to wash this oil, the same is delivered to the mixing device 78 and a stream of water also delivered 75

to the mixing device through the pipe 79 by means of a proportioning pump 80. The pump 80 may also be driven from the motor 65 through a variable speed device 81 and provision may be made for bringing either or both of the oil and water to a desired mixing temperature by heating devices 63 and 82 respectively. These heating devices may include heating coils 83 through which any desired heating fluid, such as hot water, may be circulated. The preferable temperature of mixing will vary with different oils but will usually be between 100 and 160° F.

Satisfactory mixing has been accomplished by merely injecting the stream of water at right angles into the flowing stream of oil, but a somewhat better mixture can be obtained by the mixing device 78 diagrammatically disclosed. This device may include a tubular member 85 surrounding the extremity of the pipe 71 to form an annular conduit 86 through which an annular stream of oil flows. A hollow member 87 having a concave upper surface 88 and positioned in an enlarged tubular member 89 is arranged such that the water entering through the pipe 71 strikes the concave surface 88 and is projected outwardly as an annular film into the annular stream of oil flowing in the annular conduit 86. Efficient mixing is thereby obtained, and the mixture may flow downwardly through the annular conduit 90 formed between the member 87 and tubular member 89 and then be forced inwardly through an annular orifice 91 between the members 87 and 89 to further mix the same. The resulting mixture then flows upwardly through the hollow member 87 and is discharged through a pipe 92. The detailed construction of this mixing device is disclosed in the copending application of Benjamin H. Thurman, Serial No. 190,673 filed February 15, 1938, now Patent No. 2,142,062, 40 dated December 27, 1938.

Additional heat may be imparted to the oil and water mixture in a heating device 93 which may be similar to the heating devices 63 and 82 and include a heating coil 83 positioned in a chamber 45 84. The mixture of oil and water is then delivered to the washing centrifugal 13 in which the water containing dissolved impurities is separated from the oil and discharged as a heavy effluent through the conduit 94 into receptacle 95. The de-watered oil is discharged through a pipe 96 into a float tank 97, which may be entirely similar to the float tank 20, for preventing loss of vacuum in a vacuum drying chamber 14 into which the oil is delivered from the float chamber 97.

It has been found that there are optimum temperatures for mixing water with the oil and for the separation of the water from oil for each oil being treated. In many operations, the temperature of the oil withdrawn from the chambers 60 28 and 29 is sufficiently high that no additional heat need be added thereto before or after mixing with water such that the heating devices 63, 82 and 93 are unnecessary. However, in certain cases it may be desirable to increase the temperature 65 of the oil or water or both before mixing, or the temperature of the mixture prior to centrifugal separation. The heating devices 63, 82 or 93 may be employed for this purpose. Ordinarily, the temperature of separation of the 70 water from the oil should be between 100° F. and 160° F., but no precise temperature applicable to every oil can be given, as the best temperature for separation will vary with the various oils.

The vacuum drying chamber 14 comprises a 75 closed casing 98 connected to the vacuum system

5 by a pipe 99. The oil is drawn into the chamber 14 by the vacuum present therein, and may be distributed by a distributing member 100 so as to drop as a film into the body of oil in the lower portion of the drying chamber 14. In order to maintain the desired temperature in the vacuum drying chamber 14, it may be provided with a heating coil 101 through which any desired heating medium, such as steam or hot water, can be circulated. The dried oil may be withdrawn from the vacuum chamber 14 by means of a pump 102 and sent to storage, or to conventional bleaching and deodorizing equipment.

In Figure 2 is shown a suitable apparatus for carrying out a modification of the de-aerating 15 step. In this modification oil is delivered from the float tank 20, which corresponds to the similar tank 20 of Figure 1, into a de-aerating chamber 103 by a pipe 104. The de-aerating chamber may be similar in construction to the 20 de-aerating chambers 28 and 29 of Figure 1, but is arranged for the continuous flow of oil therethrough. This chamber may comprise a closed casing 104 connected to a vacuum system, such as that shown in Figure 1, by the pipe 72, and 25 may be provided with an agitator 36 and heating coil 40. Oil is continuously withdrawn through the pipe 105 by a pump such as the pump 64 of Figure 1 and the oil subsequently washed and dried as discussed with reference to Figure 1. 30 By maintaining the chamber 103 relatively full of oil and agitating the same under vacuum conditions, substantially all of the air in the oil and any desired amount of water can be withdrawn from the oil so as to break the previously 35 discussed complex emulsion. The time the oil is treated in the de-aerating chamber 103 of Figure 2 or the chambers 28 and 29 will depend upon the type of oil being treated and the amount of air and complex emulsion present therein. Ordinarily this time will range between thirty 40 minutes and one hour, but in some cases this time may be as low as ten minutes.

Thus, the process and apparatus of the present invention enable oil to be washed by admixing 45 water therewith, out of contact with the atmosphere and without mechanical agitation, such that the water containing dissolved impurities can be substantially completely centrifugally separated from the oil. Also, the oil discharged from the refining operation can be treated to remove air therefrom, thereby rendering soluble in water, water-insoluble complex emulsions often found in such refined oils so that the washing operation may be efficiently carried out. The 50 oil is usually discharged from the refining operation at temperatures between 100 and 160° F., and such temperatures are ordinarily maintained in the system. The steam coils 40 provided therein are effective for this purpose. The stability of 55 the complex emulsion above described will determine the length of time necessary to maintain a body of oil in the de-aerating chamber 28 or 29. In most cases, a period of from thirty minutes to one hour will be found sufficient, such that the 60 chambers 28 or 29 should ordinarily be designed to hold at least the amount of oil which is refined in the refining system during an hour's operation. By opening a selected valve 46 associated with each de-aerating chamber of Figure 1, the 65 period during which oil is allowed to remain in a de-aerating chamber can be made less than that determined by the full capacity of the chamber.

While the precise de-aerating equipment dis- 75

closed is preferred, other types may, of course, be employed; for example the automatic valves 32, 33, 59 and 59' of Figure 1 may be directly controlled by the floats 48 or 48' or other level-responsive devices, thus eliminating the fluid pressure control. The system of valve operation disclosed, however, provides for greater flexibility in the positioning and construction of the de-aerating apparatus. As before stated, open tanks 10 may frequently be employed, but the employment of vacuum renders the operation more rapid, thus reducing the size of the necessary equipment, and also preventing contact of the heated oil with the atmosphere.

15 There are disclosed the preferred embodiments of this invention, but it is to be understood that the details thereof may be varied within the scope of the following claims.

I claim as my invention:

20 1. The process of removing residual impurities from previously refined animal and vegetable oils, which comprises, continuously mixing an advancing stream of water with an advancing stream of oil in a closed mixing zone, for a brief 25 period out of contact with the air and without substantial mechanical agitation producing a difficultly separable emulsion, advancing the mixture of water and oil continuously to a centrifugal separator, and centrifugally separating the 30 water containing dissolved impurities from said oil.

2. The process of removing residual impurities from alkali refined vegetable and animal oil, which comprises, continuously mixing an advancing stream of said oil with an advancing stream of water in a closed mixing zone without mechanical agitation, and separation water containing dissolved impurities from said oil.

3. The process of removing residual impurities from alkali refined animal and vegetable oil, which comprises, continuously subjecting a body of said oil to vacuum treatment to remove air therefrom, and thereafter washing said oil with water by mixing a stream of oil with a stream of water 45 without substantial mechanical agitation producing a difficultly separable emulsion and separating said water containing dissolved impurities from said oil.

4. The process of removing residual impurities from alkali refined vegetable and animal oils, which comprises, continuously removing air from said oil and thereafter mixing water with said

oil, without substantial mechanical agitation producing a difficultly separable emulsion, and separating said water from said oil.

5. The process of removing residual impurities from alkali refined vegetable and animal oils, which comprises, forming a body of said oil in a closed chamber, subjecting the upper surface of said body to subatmospheric pressure for a period of time between approximately thirty minutes and one hour, thereafter mixing water with 10 said oil without substantial mechanical agitation producing a difficultly separable emulsion, and separating said water from said oil.

6. The process of removing residual impurities from animal and vegetable oils discharged from 15 a refining operation, which comprises, continuously mixing an advancing stream of water with an advancing stream of oil in a closed mixing zone out of contact with the air and without mechanical agitation producing a difficultly separable 20 emulsion, and centrifugally separating the water containing dissolved impurities from said oil at a temperature sufficiently elevated to facilitate centrifugal separation.

7. The process of removing residual impurities from alkali refined vegetable and animal oil, which comprises, continuously mixing an advancing stream of said oil with an advancing stream of water in a closed mixing zone without mechanical agitation, and thereafter centrifugally separating water containing dissolved impurities from 30 said oil.

8. The process of removing residual impurities from alkali refined vegetable and animal oil, which comprises, continuously mixing an advancing stream of said oil with an advancing stream of water in a closed mixing zone at a temperature between 100 and 160° F. and without mechanical agitation, and centrifugally separating said water containing dissolved impurities from 40 said oil.

9. The process of removing residual impurities from alkali refined animal and vegetable oil, which comprises, subjecting a body of said oil to vacuum treatment to remove air therefrom, 45 thereafter mixing said oil with water in a closed system out of contact with the air and without mechanical agitation, and centrifugally separating said water containing dissolved impurities from said oil.
